UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

SEWING-MACHINE.

1,296,002.

Specification of Letters Patent.

Patented Mar. 4, 1919.

Application filed November 16, 1914. Serial No. 872,469.

To all whom it may concern:

Be it known that I, JAMES R. MOFFATT, a citizen of the United States, residing at Chicago, in the county of Cook, State of Illinois, have invented certain new and useful Improvements in Sewing-Machines, of which the following is a description, reference being had to the accompanying drawing, and to the figures of reference marked 10 thereon.

The invention relates to new and useful improvements in sewing machines, and more particularly to machines which are adapted to stitch an inelastic lining strip or the like 15 to an elastic body fabric.

An object of the invention is to provide a machine of the above character with a gathering or feeding member which engages the elastic body fabric and feeds the same to the 20 stitching machine slightly faster than the inelastic strip is fed by the feeding mechanism of the machine.

A further object of the invention is to provide a device of the above character 25 wherein the gathering member is positively moved back and forth through means connected with the needle bar, and wherein said gathering member is positively raised and lowered in proper timed relation to its forward and backward movements.

A still further object of the invention is to provide a machine of the above character wherein the gathering blade is yieldingly 35 pressed into engagement with the material, and an adjusting stop is provided for limiting the downward movement of the gathering member so the same may be raised from the material for the backward or return movement of the gathering member.

40 A still further object of the invention is to provide a machine of the above character with devices for laying a thread across the edge of the body fabric for joining an edging thereto, which thread-laying devices are 45 positively actuated.

In the drawings, which show by way of illustration one embodiment of the invention,—

50 Figure 1 is a front view of a portion of the machine having my improvements applied thereto;

Fig. 2 is an end view thereof;

Fig. 3 is a rear view of the machine;

Fig. 4 is an enlarged detail sectional view

on the line of the feed, many of the parts being omitted for the sake of clearness;

Fig. 5 is a detail partly in section on the line of feed, showing the gathering member as it is moving into engagement with the fabric;

Fig. 6 is a similar view showing the gathering member feeding the fabric forward;

Fig. 7 is a view showing the gathering member at the extreme rearward end of its stroke;

Fig. 8 is a view in plan, showing the thread-laying devices which coöperate with the needles;

Fig. 9 is a detail in front elevation, showing the position of the needles, the thread 70 guide and the thread-laying hook, when said thread-laying hook is at the forward end of its stroke;

Fig. 10 is a plan view of the same;

Fig. 11 is a bottom plan view showing a 75 lining strip and an edging attached to a body fabric by my improved mechanism.

Fig. 12 is a perspective view, of parts detached, showing the controlling plate and one member of the toggle for raising and 80 lowering the gathering member.

Fig. 13 is a view more or less diagrammatic, showing the controlling plate for lifting the gathering blade, with said plate in its lower position.

Fig. 14 is a similar view, showing the plate in its raised position.

Fig. 15 is a detail, showing in side elevation the yoke and the cam for operating the same, which yoke oscillates the gathering 90 blade.

In the drawings, I have shown the invention as applied to a sewing machine, which consists of a work support 1, having an overhanging arm 2 in which reciprocates a 95 needle bar 3. The needle bar 3 is connected by a link 4 to a needle lever 5 which is of the usual construction. This needle bar, as herein shown, is provided with three needles, 6, 7 and 8. The needles 7 and 8 are located 100 at some distance from the needle 6, and are the edge-stitching needles.

Coöperating with the needles beneath the work support is any suitable complementary stitch-forming mechanism. The machine is particularly adapted for stitching a binding strip, indicated at L, Fig. 11, to a body fabric, indicated at B, and also for attach-

ing an edging, indicated at E in this figure. The needle 6 produces the line of stitching 6^a in Fig. 11, while the needles 7 and 8 produce the lines of stitching 7^a and 8^a, respectively.

- The body fabric is fed over the work support, as shown in Fig. 4, while the lining strip L is led through a guide 9 attached to a bracket 10 beneath the work support. 10 The delivering end of this guide registers with the slot 11 in the work support, and the lining strip passing through the guide is led underneath the separator plate 12 and thence to the stitching mechanism. 15 The edging E is fed through a guide 13, adjustably attached by screws 14 to the guide 9. The edging passes up through a slot in the work support underneath the separating plate 12. The guides 9 and 13 20 are both carried by the bracket 10. The separator plate 12 is attached to the upper face of the work support and adjacent one side of the separator plate is an edge guide 15, which directs the edge of the body fabric 25 passing over the edge of the separator plate underneath the presser foot 16. The presser foot 16 is mounted on a presser bar 17, which is carried by the overhanging arm 2.

Coöperating with the needles 7 and 8 is 30 a thread laying hook 18. This thread-laying hook 18 has a shoulder 19 thereon. The thread for the thread-laying hook is led through a guide eye 20 carried by an arm 21. This arm 21 is mounted beneath the 35 work support, and is moved positively back and forth in a direction parallel to the line of feed. The thread-laying hook 18 is carried by an arm 22 attached to a vertical shaft 23, mounted to oscillate in bearings 40 24. The arm 22 has a ball joint 25. A link 26 is pivoted at one end of the ball joint 25, and at its other end to the needle lever extension, so that, as the needles are reciprocated, the thread-laying hook 18 is oscillated back and forth in timed relation 45 thereto.

The shaft 23 which forms the pivotal axis for the arm 22 is so disposed that the hook moves in a direction substantially at 50 right angles to the line of feed. The thread guide 20, as above noted, moves in a direction substantially parallel with the line of feed. The needle 7, as clearly shown in Fig. 9 of the drawings, is slightly lower than the 55 needle 8. The thread-laying hook and the guide eye are so timed that the thread is engaged by the hook and a loop is formed which is carried across the needles, one strand of the loop engaging the needle 7 60 and passing in rear of the needle 8, while the other strand of the loop passes in rear of both needles. It will thus be seen a loop is formed in the thread which is engaged by the needle 7, and the loops are stitched in 65 this way to the body fabric. This serves as

a tying means for joining the lines of stitching and securing firmly the edging to the body fabric. A single looper preferably co-operates with the two needles 7 and 8 beneath the work support, and operates to tie 70 together the lines of stitching beneath the fabric.

The fabric is fed to the stitching mechanism by a feed dog 35. This feed dog is carried by a feed bar 36 moved up and down 75 by an eccentric 37 on the main shaft 34. The feed bar is pivoted to a feed rocker 38, and this feed rocker is oscillated by an arm 39, connected through a link 40 with a crank on the forward end of the shaft 34. This 80 feed operating mechanism is of the usual type, and further description thereof is not thought necessary. The feed dog is raised into engagement with the fabric, and then is moved rearwardly to feed the fabric forward; then lowered to disengage the fabric and returned for its next feeding stroke.

My machine is particularly adapted for stitching an inelastic lining strip to an elastic body fabric. In order to prevent the 90 elastic body fabric from stretching as it is fed through the stitching mechanism, I have provided a gathering or feeding member 41, which is in the form, as herein shown, of a gathering blade. This gathering blade is 95 adapted to engage the body fabric on the separator plate, and to move forward to carry the fabric over the separating plate and crowd the same underneath the upturned end 16^a of the presser foot 16. 100

The gathering blade is pivotally connected to a support 42. The support 42 is formed in two sections. The upper section includes a rod 43, and this rod is mounted in a shank 44, which is adjustably attached 105 to the lower section of the support. The upper part 45 of the lower portion of the support is provided with a rib which engages a groove in the shank 44. The rib is slotted at 46, and a screw 47 passing through 110 the slot into the shank 44 holds the two sections adjustably connected together. The rib and slot prevent the sections from turning one on the other. The gathering blade 41 is pivoted at 48, to the lower portion of 115 the support 42. A spring 49 normally depresses the gathering member so that the same is caused to yieldingly engage the fabric.

A stop arm 50 is pivoted at 51 to the support 42, and the lower end of this arm extends underneath the gathering blade and serves as a stop for limiting the downward movement of the gathering blade through the action of the spring thereon. The arm 125 50 has an offset 52, which is slotted and a screw 53 passing through the slot holds the arm in adjusted positions on the support. By shifting this arm, the position of the lower end thereof may be varied, and thus 130

the position of the limiting stop for the gathering member varied.

The rod 43 is pivoted at 54 to a lever 55 fulcrumed at 56 on a bracket 57. The bracket 57 is connected to the overhanging arm. The other end of the lever 55 is pivoted at 58 to the link 59. The link 59 is pivoted to a second link 60 which in turn is pivoted to an arm 60^a, which is fixed to the outer end of the shaft 28 mounted in the bearings 29 and 30 on the overhanging arm. This shaft 28 carries a rearwardly extending arm 31, to which is attached a link 32. The link 32 is in turn connected to a pivoted fork 33 coöperating with an eccentric on the main shaft 34. The arm 31 is slotted so that the pivot for the link 32 may be adjusted for varying the oscillations of the shaft 28.

The link 60 has an integral arm 60^b attached thereto and this arm carries a pin 60^c having a roller 60^d which engages a slot 60^e formed in a plate 60^f. The plate 60^f is loosely journaled on the shaft 28. A link 60^g is pivoted to the plate 60^f and to a rearwardly projecting lug 60^h carried by the presser bar 17. The links 59 and 60 are toggle links and their movements are controlled by the slot 60^e, in which the roller carried by the arm 60^b moves. In other words, as the arm 60^a oscillates, the roller will ride up and down in the slot. The roller fits loosely in the slot and the position of this slot is such, relative to the axis of the shaft 28, that there is very little lateral movement imparted to the link 60 during the oscillations of the arm 60^a. This causes the link 59 to oscillate the lever 55 and the throw of the lever 55 is substantially the same as the throw of the arm 60^a. When the machine is at rest and the parts are not moving, the lifting of the presser foot will cause the link 60^g to swing the plate 60^f and this swinging of the plate 60^f causes the inclined portion of the side wall of the cam slot 60^e to contact with the roller 60^d and oscillate the links 59 and 60. The roller 60^d is below a horizontal line passing through the axis of the shaft 28, and, therefore, an upward movement of the plate will force the pin to the right, as viewed in Fig. 2, thus buckling further the toggles 59 and 60, and will raise the outer end of the lever 55 and also the gathering blade from the fabric.

The bracket 57 is provided with a slot 61 and a screw 62 passing through the slot holds the bracket in adjusted position on the overhanging arm. A stop screw 63 extends through the bracket and engages the screw 62 to aid in holding the bracket in adjusted positions. The adjustment of the bracket is in a direction transversely of the line of reciprocation of the needle bar, so that the pivotal support 54 of the supporting member for the gathering blade may be adjusted toward and from the line of reciprocation of the needle bar.

A sleeve 64 slides freely up and down on the rod 43. This sleeve is pivoted at 65 to a bracket 66, clamped to the needle bar 3. The bracket extends rearwardly of the needle bar, and has a fork 67, which slidably engages the presser bar 17, thus holding the bracket from twisting about the needle bar. As the needle bar reciprocates up and down, the sleeve 64 will slide up and down on the rod 43. If the pivotal point 54 is adjusted so as to be a greater distance from the line of reciprocation of the needle bar than the center of the sleeve 64, then the sleeve sliding up and down on the rod 43 will oscillate the same about said pivotal point 54. This pivotal point 54 may be adjusted by adjusting the bracket 57, and by this adjustment, the throw of the rod 43 about the pivotal point 54 may be varied.

As above noted, if this pivotal point 54 is in line with the center of the sleeve, then no vibration whatever will be imparted to the support for the gathering member.

From the above construction, it will be apparent that I have provided a support for the gathering member, on which the gathering blade is pivotally mounted, so it may be yieldingly pressed into contact with the fabric. A stop is also provided to limit the downward movement of the gathering member, and this permits said gathering blade to be lifted from the fabric when the support for said blade is raised.

The support for the gathering blade is raised and lowered through the oscillations of the lever 55, and is oscillated back and forth through the reciprocations of the needle bar.

The oscillations of the lever 55 are so timed relative to the reciprocations of the needle bar, and the movements of the main feed dog 35, that said gathering member is moved into engagement with the fabric when the needles begin the first part of their upward movement, and when the needles are clear of the fabric and the action of the main feed dog takes place. This gathering member will engage the upper face of the body fabric and move the same forward, crowding it underneath the upturned end 16^a of the presser foot. The gathering member is then raised entirely free of the fabric and is returned for its next feeding stroke.

The oscillations of the arm 60^a are brought about by the usual three-cornered cam 33^a and this cam gives a movement to the arm and then a dwell, so the arm dwells while the gathering blade is in its forward position and during the feed of the fabric by the main feed dog. As is clearly shown in Fig. 125 13 of the drawings, when the presser foot is on the fabric, the controlling plate 60^f is in its lower position and the movements of the arm 60^a will cause the roller 60^d to move up in the vertical portion of the slot 60^e, and 130

this will hold the links 59 and 60 from bending, and, therefore, the lever 55 will be raised by this movement of said arm 60^a. The downward movement of the arm 60^a through 5 the links, accomplishes the lowering of the end of the lever 55.

The length of the stroke of the arm 60^a may be adjusted, as above noted, and this will vary the extent of oscillation of the 10 lever 55 and thus vary the up and down movement of the gathering blade.

In Fig. 14 of the drawings, I have shown the controlling plate 60^a shifted through the lifting of the presser bar either by the 15 treadle or the hand lever thereof. This lifting of the controlling plate 60^a occurs when the machine is at rest. The slot 60^b now becomes a cam slot operating upon the roller 60^b to shift the link 60, buckling the 20 toggles as indicated in dotted lines in this view, and this depresses the rear end of the lever 55 and thus raises the gathering blade. The roller 60^b is so positioned in the slot that the first movement of the 25 presser bar starts to raise the presser foot before the gathering blade is raised, but the movements of the parts which lift the gathering blade are so related that said gathering blade will be raised faster than 30 the presser foot and to a point slightly above the presser foot.

In other words, the movement of the gathering blade when the presser foot is raised, is a differential movement relative 35 to the presser foot, and brings the gathering blade well above the presser foot to facilitate the insertion or removal of the material.

It will also be noted that the support 42 40 for the gathering blade may be vertically adjusted to vary the normal position of said blade when working with fabrics of different thicknesses.

The stroke of the gathering member is 45 preferably so regulated that it is slightly greater than the feed stroke of the feed dog. This results in a feeding of the body fabric slightly faster than the body fabric is carried away from the needles by the 50 main feed dog, and, therefore, the body fabric will be gathered sufficiently to prevent stretching of the same due to the following feeding movement of the fabric by the feed dog.

55 The feeding member 41 may operate upon the fabric so as to prevent the fabric being fed thereby from being stretched relative to the body fabric, or said feeding member may gather the strip being fed, or 60 again, said member may ruffle the strip being fed. The result of the feeding member upon the strip depends upon the character of the material and upon the throw of said feeding member.

65 It is obvious that minor changes in the

details of construction and arrangement of parts may be made, without departing from the spirit of the invention as set forth in the appended claims.

Having thus described my invention, 70 what I claim as new and desire to secure by Letters Patent is:—

1. The combination of a work support, stitching mechanism, feeding mechanism, a feeding member for engaging the material 75 on the work support in advance of the stitching mechanism, means for actuating said feeding member including a support for said member, means for positively raising and lowering said support, means actuated by the needle bar of the stitching mechanism for moving said feeding member back and forth, a presser foot, means for raising the presser foot and means for raising the support for the feeding member with the 80 presser foot.

2. The combination of a work support, stitching mechanism, feeding mechanism, a feeding member for engaging the material 85 on the work support in advance of the stitching mechanism, means for actuating said feeding member including a support for said member, a lever attached to the upper end of said support, means for positively oscillating the lever for raising 90 and lowering the support, means for engaging said support intermediate its ends for moving the same back and forth, a presser foot, means for raising the presser foot and means for raising the support for 95 the feeding member with the presser foot.

3. The combination of a work support, stitching mechanism, feeding mechanism, a feeding member for engaging the material 100 on the work support in advance of the stitching mechanism, means for actuating said feeding member including a support for said member, a lever pivoted to the upper end of said support, means for positively oscillating said support for raising and 105 lowering said support, means attached to the needle bar and reciprocating therewith for engaging the support intermediate its ends for moving the feeding member back and forth, a presser foot, means for raising the presser foot and means for raising the support for the feeding member with the 110 presser foot.

4. The combination of a work support, stitching mechanism, feeding mechanism, a 115 gathering member for engaging the material on the work support in advance of the stitching mechanism, means for actuating said gathering member including a support for said gathering member, a lever pivotally connected with the upper end of said support, a bracket for supporting said lever, means for positively oscillating the lever for moving the support up and down, a 120 sleeve slidably mounted on said support, 125

130

devices for attaching said sleeve to the needle bar, said sleeve being so disposed relative to the connection of the lever to the support as to oscillate the support as 5 the needle bar moves up and down, a presser foot, means for raising the presser foot and means for raising the support for the feeding member with the presser foot.

5. The combination of a work support, 10 stitching mechanism, feeding mechanism, a gathering member for engaging the material on the work support in advance of the stitching mechanism, means for actuating said gathering member including a support for 15 said gathering member, a lever pivotally connected with the upper end of said support, a bracket for supporting said lever, means for positively oscillating the lever for moving the support up and down, a sleeve 20 slidably mounted on said support, devices for attaching said sleeve to the needle bar, said sleeve being so disposed relative to the connection of the lever to the support as to oscillate the support as the needle bar moves 25 up and down, means for adjusting said bracket transversely of the line of reciprocation of the needle bar whereby the throw of the support for the gathering member may be varied, a presser foot, means for rais- 30 ing the presser foot and means for raising the support for the feeding member with the presser foot.

6. The combination of a work support, 35 stitching mechanism, feeding mechanism, a gathering member for engaging the material on the work support in advance of the stitching mechanism, means for actuating said gathering member including a support for 40 said gathering member, means for pivotally connecting the gathering member to said support, a spring for depressing the gathering member, a stop for limiting the downward movement of said gathering member, and means for moving said support back and 45 forth and up and down.

7. The combination of a work support, 50 stitching mechanism, feeding mechanism, a gathering member for engaging the material on the work support in advance of the stitching mechanism, means for actuating said gathering member including a support for 55 said gathering member, said gathering member being pivotally connected to said support, a spring for normally pressing said member toward the work support, an adjust- 60 able arm pivotally connected to said support and extending underneath said member for limiting the downward movement thereof, when the support therefor is raised, and means for moving said support back and forth and up and down.

8. The combination of a work support, 65 stitching mechanism including a needle bar, feeding mechanism, a gathering blade for engaging the material on the work support

in advance of the stitching mechanism, means for actuating said gathering blade including a support for said gathering blade, said gathering blade being pivotally connected to said support, a spring for normally pressing said blade toward the work support, an arm pivotally connected to said support and extending underneath said blade for limiting the downward movement thereof, a lever pivotally connected to the upper end of said support, means for oscillating the lever for raising and lowering said support, a sleeve slidably mounted on said support, and a bracket attached to the needle bar to which said sleeve is pivoted whereby the reciprocation of the needle bar will oscillate said support on its connection with said lever.

9. The combination of a work support, 70 stitching mechanism including a needle bar, feeding mechanism, a gathering blade for engaging the material on the work support in advance of the stitching mechanism, means for actuating said blade member including a support for said blade, said gathering blade being pivotally connected to said support, a spring for normally pressing said blade toward the work support, an adjustable arm pivotally connected to said support and extending underneath said blade 75 for limiting the downward movement thereof, a lever pivotally connected to the upper end of said support, means for oscillating the lever for raising and lowering said support, a sleeve slidably mounted on said support, a bracket attached to the needle bar to which said sleeve is pivoted whereby the reciprocation of the needle bar will oscillate said support on its connection with said lever.

10. The combination of a work support, 80 stitching mechanism including a needle bar, and means for reciprocating the same, an overhanging arm in which said needle bar reciprocates, a shaft mounted in bearings in said overhanging arm, means for oscillating said shaft, a gathering member for engaging the material on the work support in advance of the needle, a support for said gathering member, a lever for raising and lowering said support, means for positively oscillating said lever from said shaft, means for moving said support back and forth, a presser foot, means for raising the presser foot and means for raising the support for the feeding member with the presser foot.

11. The combination of a work support, 85 stitching mechanism including a needle bar, and means for reciprocating the same, an overhanging arm in which said needle bar reciprocates, a shaft mounted in bearings in 90

said overhanging arm, means for oscillating said shaft, a gathering member engaging the material on the work support in advance of the stitching mechanism, a lever 5 connected to the overhanging arm, a support for the gathering member, said support being pivotally connected to said lever, an arm on said shaft, toggle links connecting said arm to said lever, and means for moving 10 said support back and forth.

12. The combination of a work support, stitching mechanism including a needle bar, and means for reciprocating the same, an overhanging arm in which said needle bar 15 reciprocates, a shaft mounted in bearings in said overhanging arm, means for oscillating said shaft, a gathering member engaging the material on the work support in advance of the stitching mechanism, a lever connected 20 to the overhanging arm, a support for the gathering member, said support being pivotally connected to said lever, an arm on said shaft, toggle links connecting said arm to said lever, means for moving said support 25 back and forth, and means for holding said links from substantial movement relative to each other as the arm oscillates.

13. The combination of a work support, stitching mechanism including a needle bar, 30 and means for reciprocating the same, an overhanging arm in which said needle bar reciprocates, a shaft mounted in bearings in said overhanging arm, means for oscillating said shaft, a gathering member engaging the 35 material on the work support in advance of the stitching mechanism, a lever connected to the overhanging arm, a support for the gathering member, said support being pivotally connected to said lever, an arm on said 40 shaft, links connecting said arm to said lever, means for moving said support back and forth, means for holding said links from substantial movement relative to each other as the arm oscillates, and means whereby 45 said links may be moved by the presser foot lifting mechanism when the machine is stopped for raising the gathering member from the fabric.

14. The combination of a work support, 50 stitching mechanism, an overhanging arm, a shaft mounted in said overhanging arm, a feeding member located in advance of the stitching mechanism, means for moving the feeding member back and forth, and means 55 for positively raising and lowering said feeding member, said means including a lever, an arm carried by the shaft, toggle links connecting the arm to the lever, and means for holding the toggle links from sub- 60 stantial movement relative to each other during the oscillation of the arm, whereby the oscillations of the arm are imparted to the lever through said toggle links.

15. The combination of a work support, 65 stitching mechanism, an overhanging arm,

a shaft mounted in said overhanging arm, a feeding member located in advance of the stitching member, means for moving the feeding member back and forth, and means for positively raising and lowering said feeding member, said means including a lever, an arm carried by the shaft, toggle links connecting the arm to the lever, means for holding the toggle links from substantial movement relative to each other during the oscillations of the arm, whereby the oscillations of the arm are imparted to the lever through said toggle links, and means whereby said toggle links may be buckled when the machine is at rest for raising the gathering 75 member.

16. The combination of a work support, stitching mechanism, a feeding member located in advance of the stitching mechanism, means for moving said feeding member back 80 and forth, and means for raising and lowering the feeding member including a lever connected to said feeding member, a shaft, an arm carried by the shaft, toggle links connecting the arm to the lever, a normally sta- 85 tionary plate having a slot therein, an arm carried by one of the toggle links and having a pin engaging said slot, said slot being so disposed as to hold the toggle members from 90 substantial movement relative to each other during the oscillation of said arm.

17. The combination of a work support, stitching mechanism, a feeding member located in advance of the stitching mechanism, means for moving said feeding member back 100 and forth, and means for raising and lowering the feeding member including a lever connected to said feeding member, a shaft, an arm carried by the shaft, toggle links connecting the arm to the lever, a normally sta- 105 tionary plate having a slot therein, an arm carried by one of the toggle links and having a pin engaging said slot, said slot being so disposed as to hold the toggle links from 110 substantial movement relative to each other during the oscillation of said arm, and means for oscillating said plate when the presser foot is lifted so as to buckle said toggle links 115 for raising the feeding member.

18. The combination with a work support, a stitch-forming mechanism, and a feeding mechanism, including a presser foot, of a feeding member independent of the foot for engaging the material on the work support in advance of the stitch-forming mechanism, 120 means including a cam slot and a pin co-operating therewith for actuating said feeding member in timed relation to the movements of the feeding mechanism, and means under the control of the operator for raising the presser foot and shifting the cam slot and pin to simultaneously effect the raising of the feeding member.

19. The combination with a work support, a stitch-forming mechanism and a feeding 125

mechanism including a presser foot, of a feed member independent of the foot for engaging the material on the work support in advance of the stitch-forming mechanism, 5 means for imparting a positive four motion movement to said feeding member, said means including an adjustable connection for varying the up and down movement of said feeding member, and means under con-

trol of the operator for raising the foot and 10 for positively raising the feeding member therewith.

In testimony whereof, I affix my signature, in the presence of two witnesses.

JAMES R. MOFFATT.
